(57) **CLAIM**

We claim the ornamental design for a hole pattern for lighter,
as shown and described.

DESCRIPTION

FIG. 1 is a perspective view of a hole pattern for lighter;
FIG. 2 is an enlarged view thereof;
FIG. 3 is a front elevation view of FIG. 1; and,
FIG. 4 is a rear elevation view of FIG. 1.

The broken line disclosure of a lighter is shown for illustrative purposes only and forms no part of the claimed design.
